UNITED STATES PATENT OFFICE.

LOUIS EDELSTEIN, OF DICKSON, PENNSYLVANIA.

BED.

1,355,545.

Specification of Letters Patent. Patented Oct. 12, 1920.

Application filed January 27, 1919. Serial No. 273,463.

To all whom it may concern:

Be it known that I, LOUIS EDELSTEIN, a citizen of the United States, residing at Dickson city, in the county of Lackawanna and State of Pennsylvania, have invented 5 certain new and useful Improvements in Beds; and I do hereby declare the following to be a full, clear, and exact description of the invention, such as will enable others skilled in the art to which it appertains to 10 make and use the same.

Among the principal objects which the present invention has in view is; to provide connecting means for avoiding the use of 15 bolts, nails, screws and other metallic fastening devices; and to provide attaching devices constructed to interlock with each other.

Drawings.

20

Figure 1, is a longitudinal sectional view of a bed constructed in accordance with this invention.

Fig. 2, is a perspective view of a fragment 25 of one of the corner posts of the bed, showing in detail one of the sockets for receiving one of the side rails.

Fig. 3, is a perspective view of a fragment 30 of one of the side rails, showing an end thereof and a socket for the slat rail hanger.

Fig. 4 is a detail view in perspective of the slat rail hanger.

Fig. 5 is a perspective view of an end 35 portion of said slat rail.

Description.

As seen in the drawings, the numeral 1 is used to designate the corner posts of the 40 bed having attached the usual head and foot board rails 2. Each of the corner posts has a socket 3 which is spaced from the lower end thereof to receive the tenons 6 of the side boards 5. The side walls 4 of the 45 sockets 3 converge toward their lower ends and are undercut to retain the tenons 6 when the same are disposed therein.

The side boards of the bed are provided 50 with tenons 6 tapered to their lower ends. The tenons 6 fit the lower portions of the sockets 3, and are held snugly therein.

The side boards 5 are provided adjacent 55 the opposite ends thereof with undercut sockets 7, tapered toward their lower ends and adapted for holding in service brackets 8. The said brackets 8 have each a body

portion 9, and a head 10 of less width than the said body portion and the inner face of which is inclined as at 11. An outwardly flared tenon 12, protrudes from the body 60 portion 9 and is shaped in correspondence with the socket 7, and with the lower portion thereof, the undercut walls of said tenons and sockets engaging to hold the brackets firmly in service relation to the side 65 boards 5.

The ledge rails 13 are provided for supporting the slats of the bed. Each of said rails has recesses 14, near its ends for receiving a head 10. As shown in Fig. 5, the 70 inner wall of each recess is inclined in correspondence with the face 11 of the head 10 on the bracket 9. It will be seen that when the parts are assembled, the overhanging portion of the head 10 extends within 75 the recess 14 when the lower edge of the ledge rail 13 rests on the body of the bracket 8.

In assembling the bed, the side boards are first positioned in the head and foot members by inserting the tenons 6 in the sockets 3, and forcing the said tenons downwardly so that they wedge in position. The rails 13 are then positioned upon the body portion 9 of said brackets 8, the heads 10 being 80 disposed in the recesses 14. The tenons 12 of the brackets 8 are then placed in the sockets 7, and the brackets are forced down. It will be seen that the said heads enter the recesses 14 in the rails 13, and that the 85 tenons 12 will be wedged in place in the sockets 7.

In this manner it is evident that the whole 90 structure is locked together without using nails, screws, or similar fastening means.

From the foregoing, it will be seen that 95 when constructing a bed in conformity with the present invention, the structure may be readily and easily dismembered and each member being integral may be thoroughly 100 inspected to eliminate any vermin or other lodgments. Also the parts being separable in the manner disclosed, they may be readily sanitized or fumigated.

Claims.

105

1. A bed structure comprising a plurality of side boards, each having adjacent the opposite ends thereof, sockets, said sockets opening toward the center of said structure, 110 the upper end of the openings being larger than the lower ends thereof, and the sides

- of said socket overhanging at the lower ends thereof; a plurality of ledge rails co-extensive with said side boards, each of said rails having sockets adjacent their ends, 5 said sockets being alined in service with the said sockets in the side boards; and a plurality of brackets for supporting said ledge rails, each of said brackets having an anchoring member adapted for extension 10 within to be held by said sockets in said side boards, said brackets having each an upwardly extending head for engaging said ledge rails to draw the same toward the side board with which said rail is associated. 15
2. A bed structure comprising a plurality of side boards, each having adjacent the opposite ends thereof, sockets, said sockets opening toward the center of said structure,

the upper end of the openings being larger 20 than the lower ends thereof and the sides of said socket overhanging at the lower ends thereof; a plurality of ledge rails co-extensive with said side boards, each of said rails having sockets adjacent their ends, said 25 sockets being alined in service with the said sockets in the side boards; and a plurality of brackets for supporting said ledge rails in service, each of said brackets having a tenon provided with undercut side edges 30 for engaging said sockets in said side boards and each of said brackets having an undercut head for engaging said sockets in said ledge rails to prevent lifting said ledge rails independently of said brackets. 35

In testimony whereof I affix my signature.

LOUIS EDELSTEIN.
